MILEAGE INDICATOR FOR BICYCLES AND THE LIKE

Eugenio Pagani, Milan, Italy, assignor to Fratelli
Pagani S.p.A., Milan, Italy

Filed July 18, 1966, Ser. No. 3,116

Claims priority, application Italy Apr. 7, 1966

Term of patent 14 years

(Cl. D52—6)

FIGURE 1 is a perspective view of a mileage indicator for bicycles;

FIGURE 2 is a front elevational view;

FIGURE 3 is a plan view taken from the top thereof;

FIGURE 4 is a perspective view taken from the rear and left side of FIGURE 1; and

FIGURE 5 is a plan view taken from the bottom thereof.

The essential features of the design reside in the full line portions of the drawing.

I claim:

The ornamental design for a mileage indicator for bicycles and the like, as shown.
